UNITED STATES PATENT OFFICE.

ELMER L. WILSDORF, OF EAST CLEVELAND, OHIO, ASSIGNOR OF ONE-FOURTH TO CHARLES E. MOYER AND ONE-FOURTH TO GEORGE UMSTEAD, BOTH OF CLEVELAND, OHIO.

FLYING-MACHINE.

1,288,781.

Specification of Letters Patent. Patented Dec. 24, 1918.

Application filed January 26, 1918. Serial No. 213,853.

To all whom it may concern:

Be it known that I, ELMER L. WILSDORF, a citizen of the United States, residing at East Cleveland, in the county of Cuyahoga and State of Ohio, have invented certain new and useful Improvements in Flying-Machines, of which the following is a specification.

My invention relates to improvements in flying machines of the aeroplane type in which the weight is sustained by the reaction resulting when one or more aeroplanes are moved through the air edgewise at a small angle of incidence by the application of mechanical power, through the medium of suitable propeller mechanism, and balanced by means of suitable vertically and horizontally arranged rudders.

My invention relates more particularly to improvements in aeroplanes, the primary object being to provide a new form of aeroplane adapted to present a more effective sustaining surface on its under side, as well as being adapted to more effectively maintain lateral balance. More specifically speaking, my improvements in aeroplanes consist in the provision of an aeroplane elongated in the direction of flight and having a transversely convex sustaining and stabilizing under surface, whereby a plane possessing great inherent stability is provided. A still further improvement consists in the combination, with such form of aeroplane, of an upwardly inclined prow or forward portion inclined upwardly to the common or main longitudinal plane thereof.

A further object is the provision of a combined aeroplane and hydroplane, together with improved means for controlling the same in either capacity.

A still further object is to provide improved rudders and stabilizers adapted to coöperate with each other and with the aeroplane through suitable operating and control mechanism, whereby to control the direction of flight and maintain or restore equilibrium as the varying exigencies of flight may require.

A still further object is the provision of improved rudder operating and controlling mechanism adapted to be operated by a single hand wheel and steering column.

A still further object is the provision of an improved body or "chassis," together

with improved means of mounting and supporting the landing wheels therefor.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a side elevation of a flying machine constructed in accordance with this invention as it appears upon the ground or earth's surface preparatory to flight, the rear elevating and depressing horizontal plane and the operating and controlling mechanism therefor, being shown in one of their extreme positions.

Fig. 2, a side elevation of the same in flight, or upon the water as a hydroplane, the dotted line representing substantially the angle or incidence and normal inclination of the plane while in flight, or in the water, as the case may be, and the rear or horizontal rudder plane and operating mechanism therefor, being shown in a substantially reversed position to that shown in Fig. 1.

Fig. 3, a diagrammatic side elevation of the improved form of sustaining plane, and illustrating in particular the upwardly and downwardly extending prow and rudder portions of the sustaining plane and the substantial center of gravity thereof.

Fig. 4, a diagrammatic front elevation of the same, illustrating in particular the transversely convex sustaining and stabilizing surface thereof, the dotted lines illustrating the lines of air action thereon in flight.

Fig. 5, a top plan view of the improved machine, and illustrating in particular the elongated form and outline of the improved aeroplane.

Fig. 6, a transverse or cross sectional view taken on line 6—6, of Fig. 2.

Fig. 7, a similar view taken on line 7—7, 100 of Fig. 2.

Fig. 8, a perspective view of the rear end of the improved plane, the rear horizontal or tail rudder being removed, and illustrating in particular the rear elevating and depressing horizontal plane, and its mounting and the operating and controlling mechanism therefor.

Fig. 9, a fragmentary perspective view of a side portion or section of the improved sustaining plane, and illustrating in particular the side and transverse frame members 5 therefore, and the upper and lower plane or fabric coverings thereof.

Similar numerals of reference designate like parts throughout all the figures of the drawings.

10 The improved flying machine embodies an improved sustaining plane or main supporting surface 1, which is longitudinally elongated in the direction of flight and is provided with a transversely convex sustaining 15 and stabilizing surface 1^a, as shown most clearly in Figs. 4, 6, and 7, of the drawings. It will be seen that the improved sustaining plane is of substantially convexo-concave shape in cross section for the purpose of rendering the sustaining plane more inherently 20 stable by more readily maintaining or restoring lateral balance or equilibrium, as will be more readily apparent upon reference to Fig. 4, of the drawings. For the 25 purpose of giving the improved sustaining plane additional lifting power, the front or prow portion 1^b, is inclined and curved upwardly to the main longitudinal plane or axis of the sustaining plane, as a whole, and 30 as a means of providing a suitable framework for the surfaces of the sustaining plane, curved side frame members 2, of suitable form may be provided, said side members 2, being suitably supported or trussed by 35 means of suitable cross members 2^a, and longitudinally extending median members 2^b, as shown most clearly in Figs. 6, 7, and 9, of the drawings.

As a means of connecting the frame members of the aeroplane to a suitable supporting structure, as well as adapting the improved machine for use, either as an aeroplane or as a hydroplane, the front or prow portion of the aeroplane is provided, in the 45 present instance, with a downwardly and rearwardly curved median skid member 3, terminating in a main supporting member 3^a, the latter terminating in an upwardly curved skid member 3^b.

50 As a means of providing a suitable supporting or boat structure when at rest, or in the water as a hydroplane, the main supporting frame member 3^a, is provided with frame members 4, arranged in suitable form 55 to receive and carry a suitable boat or hull body 5, the latter being of suitable form as shown, and preferably provided with open sides 5^a, the front inner portion of the supporting structure or boat body 5, being provided with a suitable power unit 6, suitably 60 connected to a propeller shaft 7, carrying a suitable propeller 8. The propeller 8, is preferably mounted immediately beneath the upwardly curved front or prow portion 1^b, 65 of the aeroplane and in front of the boat

body 5, thereby being protected by the curved front skid member 3, and as a means of counter-acting the side or lateral thrust of the propeller shaft 7, during its rotation, the front under side of the aeroplane may be 70 provided with a vertical rudder 9, hingedly connected along its upper edge, as at 9^a, (see Fig. 6) and adapted to be adjusted at various angles of incidence by means of an adjusting bolt 9^b, adjustably connected to the 75 front curved skid member 3.

The supporting structure or hull body 5, may be provided with suitable ground or landing wheels 10, carried on transverse axle members 10^a, the latter being mounted in 80 suitable front and rear spring members 11 and 12, respectively. In the present instance, the front spring member 11, consists of a single length of suitable spring material bent midway of its ends to form a loop member 11^a, the latter bearing beneath the under side of the hull body 5, and terminating in coils 11^b, carrying the front axle member 10^a, the rear ends of the front spring member 11, being connected to suitable brackets 13, on 85 the boat or supporting structure 5. The rear spring 12, in the present instance, comprises two longitudinally extending side members connected at their front by means of brackets 14, and the rear axle member 10^a, in the present instance, is provided with a loop portion 10^b, adapted to straddle and clear the main supporting or skid member 3^a.

The rear end of the aeroplane is preferably provided with a horizontal tail rudder 100 15, in the present instance, hingedly connected to hinge lugs 2^c, of the aeroplane frame, said tail rudder 15, normally extending downwardly and rearwardly as shown, and being adjustably supported by means of a 105 curved threaded supporting rod 16, extending, in the present instance, from the rear skid member 3^b, said supporting rod extending through a suitable opening in the tail rudder, and being provided with adjusting 110 nuts 16^a.

As a means of controlling and regulating the horizontal direction of flight, or in other words,—the angle of incidence presented by the main sustaining plane or supporting 115 surface 1, the latter is provided at its rear under side with an elevating and depressing rudder-plane 17, extending transversely of the sustaining plane and adapted to rock on suitable trunnion members carried in suitable bearings 18^a, being mounted on the ends of depending supports 18, suitably secured to the aeroplane frame, and, if desired, the supports 18, and bearings 18^a, may be braced by means of brace wires 19.

125 As a means of controlling and rocking the rudder-plane 17, as well as adjusting and holding the same in any desired adjusted position, the front and rear portions of the rudder-plane 17, are provided with front and 130

rear pairs of cable members 20, and 21, respectively, extending forwardly over suitable sheaves 22, and being connected to rear and front cables 23 and 24, respectively, the 5 latter passing over suitable rocker segments 25^a, of a steering column supporting rocker 25. The rocker 25, is mounted in a bearing column 26, and is provided with a steering column 27, provided with a steering wheel 28.

10 As a means of providing for the lateral control of the combined aeroplane and hydroplane, the aeroplane is provided with upper and lower vertical rudders 29 and 30, respectively, the upper or plane rudder 29, being mounted above the rear portion of the 15 main plane and being connected to the lower or boat rudder 30, by means of a vertical axle or rock shaft 31, to which the rudders 29 or 30, may be keyed or otherwise suitably secured, and as a means of simultaneously actuating the rudders 29 and 30, the front portion of the upper rudder 29, is provided with oppositely extending cable members 32, extending over suitable sheaves 33, 20 at the side of the aeroplane, one of said cables extending through one end of the hollow rocker 25, and being wound upon the intersecting end of the steering column 27, the other cable extending through the opposite end of the rocker 25, and being oppositely wound on the steering column so that the cable 32, will operate in unison with the turning of the steering wheel and column in an obvious manner, and when it is desired to 25 operate the rudder-plane 17, at the same time, or simultaneously with the actuation thereof, it is obvious that a rocking motion imparted to the steering column 27, and steering wheel 28, will impart a rocking motion to the rocker 25, and thereby actuate the 30 rear and front cables 23 and 24.

From the foregoing description, taken in connection with the accompanying drawings, the operation and advantages of my invention 45 will be readily understood.

Having thus described one of the embodiments of my invention, what I claim and desire to secure by Letters Patent, is,—

1. In a hydroaeroplane, a sustaining 50 plane, a boat structure carried beneath the same, connected vertical aerial and boat rudders above and at the rear of said plane and boat structures, respectively, a horizontal rudder-plane beneath said sustaining 55 plane and at the rear of said boat rudder, and a horizontal downwardly inclined tail rudder adjustably mounted at the rear of said sustaining plane and said rudders and rudder-plane.

60 2. In a flying machine, an elongated sustaining plane of convexo-concave shape in cross section, a boat structure carried thereby, an elevating and depressing rudder-plane beneath the rear portion of said sustaining 65 plane, vertical steering rudders above and

below said sustaining plane respectively, a tail rudder on said sustaining plane, and a steering wheel and column operatively connected to said vertical rudders and said rudder-plane for actuating the same either singly or simultaneously.

3. In a hydroaeroplane, a sustaining plane provided with a depending boat structure and having a vertically pivoted plane connected to a boat rudder at its rear, said boat structure being provided with front and rear skid members, a propeller at the front of said boat structure beneath said plane and at the rear of said front skid member, a power unit carried by said boat structure and operatively connected to said propeller, and an elevating and depressing horizontal rudder-plane beneath the rear portion of said sustaining plane and at the rear of said boat structure.

4. In a hydroaeroplane, a sustaining plane provided with a depending boat structure and having connected vertically pivoted horizontally swinging aerial and boat rudders at its rear, said boat structure being provided with curved front and rear skid members connected to the front and rear portions of said sustaining plane, a propeller at the front of said boat structure beneath said plane and at the rear of said front skid member, a power unit carried by said boat structure and operatively connected to said propeller, and an elevating and depressing horizontal rudder-plane beneath the rear portion of said sustaining plane and at the rear of said boat structure and arranged within and protected by said rear skid member.

5. In a hydroaeroplane, a sustaining plane, a boat body carried beneath the same, a chassis therefor, ground wheels thereon, connected upper and lower vertical rudders above and below said sustaining plane, said lower rudder being at the rear of said boat body, a horizontal rudder-plane beneath said sustaining plane and at the rear of said boat body, and a steering column and column supporting rocker member operatively connected to said rudders and rudder-plane, respectively, whereby a rotary movement of said steering column will simultaneously actuate said upper and lower rudders and a rocking movement of said rocker member by said column will actuate said rudder-plane.

6. In a hydroaeroplane, a sustaining plane, a boat body, carried beneath the same, a chassis therefor, ground wheels thereon, upper and lower horizontally swinging vertical rudders projecting above and below said sustaining plane, a horizontal rudder-plane beneath said sustaining plane and at the rear of said boat body, and a steering column and column supporting rocker member operatively connected to said rudders.

and rudder-plane, respectively, whereby a rotary movement of said steering column will simultaneously actuate said vertical rudders and a rocking movement of said 5 rocker member by said column will actuate said rudder-plane.

7. In a flying machine, a sustaining plane, a boat structure carried thereby, vertical rudders carried by said sustaining plane, one 10 of said rudders being above said sustaining plane and the other below the same and at the rear of said boat structure, a horizontal rudder-plane beneath the rear portion of said sustaining plane and at the rear of said 15 boat structure, a propeller at the front of said boat structure and beneath the front portion of said sustaining plane, and a steering column and rocker member connected to said vertical rudders and rudder-plane, respectively, whereby the same may be operated either simultaneously or singly by the movements of said steering column and rocker member.

20 8. In a flying machine, a sustaining plane,

a boat structure including curved front and 25 rear median skid members carried thereby, vertically pivoted connected rudders carried by said sustaining plane, one of said rudders projecting above said sustaining plane and the other projecting below the same at the 30 rear of said boat structure, an elevating and depressing rudder-plane beneath the rear portion of said sustaining plane and arranged within and protected by said rear skid member, a propeller at the front of said 35 boat structure arranged within and protected by said front skid member, and a rotatable rocking steering device connected to said vertical rudders and rudder-plane, whereby the same may be operated by the 40 rotatable and rocking movements of said steering device.

In testimony whereof I have affixed my signature in the presence of two witnesses.

ELMER L. WILSDORF.
